CLAIM

The ornamental design for a pocket secretary with flip out panel, as shown and described.

DESCRIPTION

FIG. 1 is an exploded front perspective view of a pocket secretary with flip out panel in open condition, showing my new design;

FIG. 2 is a front, perspective view thereof, in closed condition, the undisclosed rear being the same;

FIG. 3 is a front perspective view thereof, in open condition; and

FIG. 4 is a front perspective view thereof, with part of the insert portion flipped out.

The broken lines shown on the insert portion of FIGS. 1, 3 and 4 are for illustrative purposes only and form no part of the claimed design. The remaining dashed lines in all views represent conventional stitching.
